CLAIM

The ornamental design for a digital picture frame as shown and described.

DESCRIPTION

1. Digital picture frame
  2. Digital picture frame
  - 1.1: Perspective
  - 1.2: Perspective
  - 1.3: Front
  - 1.4: Back
  - 1.5: Left
  - 1.6: Right
  - 1.7: Top
  - 1.8: Bottom
  - 1.9: Perspective view in a state of use
  - 1.10: Perspective view in a state of use
  - 1.11: Exploded
  - 2.1: Perspective
  - 2.2: Perspective
  - 2.3: Front
  - 2.4: Back
  - 2.5: Left
  - 2.6: Right
  - 2.7: Top
  - 2.8: Bottom
  - 2.9: Perspective view in a state of use
  - 2.10: Perspective view in a state of use
  - 2.11: Exploded
- The figures include surface shading, which represents contours and not surface ornamentation; the broken lines in the figures illustrate features that form no part of the claimed designs.
